UNITED STATES PATENT OFFICE.

VALENTIN JAKOB ODHNER, OF STOCKHOLM, SWEDEN.

CALCULATING MACHINE.

Application filed November 17, 1922. Serial No. 601,586.

To all whom it may concern:

Be it known that I, VALENTIN JAKOB ODHNER, a subject of the King of Sweden, and resident of Vikingagatan 30, Stockholm, in the Kingdom of Sweden, have invented certain new and useful Improvements in Calculating Machines, of which the following is a specification, reference being had therein to the accompanying drawings.

This invention relates to improvements in calculating machines provided with calculating discs of that class in which the crank for turning the calculating discs is provided with or arranged to cooperate with a locking device in order to make possible for the locking in zero position of the crank and thereby of the calculating discs. By such calculating machines the locking device, which mostly is acted upon by a spring, is usually joined to the crank handle, which is slidable in lengthwise direction, that is, at about right angles to the plane of rotation of the crank, whereby said locking device is brought out of active position by the moving outwards of the handle against the action of the spring. In order to keep the locking device in inactive position during the turning of the crank, the handle must during this turning be kept pressed outwards at about right angles to the plane of rotation of the crank, which of course renders the turning more difficult.

The object of this invention is to remove said inconveniences by the crank or the locking device or both being so arranged that said locking device may be brought out of active position by pressing the crank handle in a direction towards or away from the centre line of the crank shaft, besides which the locking device or the crank or a part which is joined to the latter is provided with or combined with a guiding device so arranged that it keeps the locking device in inactive position during the turning of the crank except when the crank is in the zero position.

In the accompanying drawings the invention is shown applied to a calculating machine. Fig. 1 is a side view of the machine provided with an embodiment of the invention. Fig. 2 is a section on the line A—A of Fig. 1. Fig. 3 shows a lengthwise section of the machine. Fig. 4 is a section on the line B—B of Fig. 3. Fig. 5 is a lengthwise section of the machine provided

with a modified embodiment of the device. Fig. 6 is an end view of the device. Fig. 7 is a section on the line C—C of Fig. 5. Fig. 8 shows schematically a combination of both embodiments shown in Figs. 1—4 and 5—7. Of the machine only so much is shown as is necessary for the explaining of the invention.

On a turnable shaft 2 that is journaled in the frame 1 of the machine are as usual arranged calculating discs 3 situated next to each other, of which discs only two are shown in the drawing. By the embodiment shown in Figs. 1—4 the crank 4 for the turning of the calculating discs, which crank is shown in the drawing fastened directly to the shaft 2, is joined to the handle 6 in such a way that said handle is swingable within certain limits about a pivot 5 in a plane that is about at right angles to the plane of rotation of the crank. The handle 6 is provided with or formed as a part 7 that is acted upon by a spring and situated at a suitable angle to the handle, which part 7 is provided with or arranged to cooperate with a locking device for the locking in zero position of the crank and thereby the calculating discs. By the embodiment shown in the drawings the free end 8 of the part 7, acts as a locking device which cooperates with a notch 9 or the like arranged in the frame of the machine. The sectional form of the crank 4 is formed as the letter U so that the part 7 without hindrance may be swung into and out of gear with the notch 9.

The locking device for the crank 4 and the calculating discs, or on the other hand part 7 of the crank, is provided with or combined with a guiding device which is intended to keep the locking device in inactive position during the turning of the crank except when the crank is in zero position. In the drawings the guiding device is, for example, shown combined with part 7. This is provided with a turnable roll 10 or the like which cooperates with a guide on the frame of the machine, which guide has the form of a ring 11 in which is arranged a notch 12 or the like corresponding to the zero position of the crank. The roll 10 may eventually be arranged on the frame and the guide 11 on the part 7.

The part 7 which is provided with the locking device 8 is joined in such a way to a locking device cooperating with the cam-discs 13 of the machine, that the cam-

disks are locked or liberated respectively when the device 8 is brought respectively out of or into gear with the notch 9. For this reason the part 7 is arranged to act upon a movable part which in the shown embodiment consists of a sleeve 14 or the like that is slidable on the shaft 2. The part 7 is provided with two rolls 15 or the like diametrically situated and acting as drivers for the sleeve 14, which rolls gear into a groove 16 or the like in the sleeve. This is for example joined to a toothed wheel, a toothed sector 19, or the like, by means of a turnable crank lever 17, 18, which toothed wheel is fastened to a shaft 20 which is journalled in the frame. One arm 17 of the lever is joined to the sleeve 14 and is movable in a groove 21 in the ring 11 which groove acts as a guide, and the arm 18 cooperates either directly with the toothed sector 19, or, as shown in the drawings, with a disc 22 or the like fastened to the shaft 20 which disc is provided with shoulders 23 for the lever. In the machine are arranged two concentric ring shaped parts 24, 25 encircling the shaft of the calculating disks, of which parts 24, 25 the latter is fastened to the frame and the part 24 is turnable and provided with teeth gearing with the toothed sector 19. In each of the rings 24, 25 there is a notch 26, 27 or the like which notches are intended to cooperate in a certain position with a roll 29 extending through an aperture 28 in the shaft 2, which roll 29 is joined to a locking device 30 for the cam-disks 13. According to Figs. 3 and 4, the crank 4 and the calculating disk 3 are in zero position, whereby the locking device 8 catches into the notch 9 in the frame, while the guiding roll 10 is in the notch 12 of the ring 11. By this position of the turnable ring 24, the roll 29 which is joined to the locking device 30 of the cam-disks is in the two notches 26, 27 which are situated opposite each other, Figs. 3 and 4, whereby the locking device is out of gear with the cam-disks 13. When the locking device 8 is brought out of gear with the notch 9, that is in inactive position, by applying a pressure upon the handle 6 in a direction from the centre line of the crank shaft the roll 10 is brought out from the notch 12 in the ring 11. During the same time the sleeve 14 is moved towards the crank 4, whereby the lever 17, 18 is swung to the position shown in Fig. 2 and turns the disc 22 and thereby the toothed sector 19 to the position indicated with dash-dot lines in Fig. 4. The toothed sector 19 turns the ring 24, so that the notch 26 in the ring is brought into the position indicated with dash-dot lines in Fig. 4, whereby the roll 29 is brought out from the two notches 26, 27 and the locking device 30 catches into the cam-disks 13. During the turning of the crank the roll 10 rolls on the ring 11 acting as a guide, except when the crank passes the zero position, when the handle 6, as is shown in the drawing, is in or near its lowest position, whereby the weight of the hand is sufficient for preventing the locking device 8 from catching into the notch 9. The roll 29 on the locking device 30, which roll in this position extends very slightly from the shaft 2, rolls during the turning of the shaft on the inner edges 31 of the rings 24, 25, so that the locking device is kept in gear with the cam-disks 13 until the ring 24 by the catching into the notch 9 of the locking device 8 is turned by the toothed sector so that the notch 26 is brought in line with the notch 27.

According to the altered embodiment shown in Figs. 5 to 7, the handle 6 provided with the part 7 is slidable within certain limits in or near the plane of rotation of the crank 4. The roll 10 on the part 7 rolls by the turning of the crank according to this embodiment on the inside of the ring 11. The part 7 of the handle is so joined to a slidable part 32 which is acted upon by a spring, that this part 32 moves in conjunction with part 7. According to the drawing, the part 32 which is intended to cooperate with the roll 29 on the guiding device 30, is for this reason provided with a turnable roll 33 or the like, which owing to the spring 34 continually lies against the inside of the ring shaped part 35 of the part 7 of the handle. The ring 25 which is fastened to the frame and encircles the shaft 2 is pierced with an aperture 36 for the part 32.

According to Figs. 5 to 7 the locking device 8 is out of gear with the notch 9, that is in inactive position, whereby the part 32 constitutes the continuation of the inside of the ring 25, so that the roll 29 is kept in the inward position and the locking device 30 catches into the cam-disks 13. During the turning of the shaft 2 the roll 29 rolls on the inside of the ring 25 and on the part 32 in the notch 36. When the locking device 8 by the moving upwards of the part 7 of the handle is brought into gear with the notch 9, the part 32 is also moved in the same direction owing to the action of the spring 34, whereby the roll 29 owing to the action of a spring or such like catches into the notch 36 thus made free, so that the locking device 30 is brought out of gear with the cam-disks.

The two embodiments shown in Figs. 1-4 and 5-7 may be combined with each other in many ways. One example of this is shown schematically in Fig. 8 where the crank handle according to Figs. 5-7, which is slidable in the plane of rotation of the crank, is combined with the toothed sector 13.

19 and with the two concentrically arranged rings 24, 25 according to Figs. 1-4. The roll 33 which owing to the action of a spring or the like lies continually against the inside of the ring shaped part 35 of the parts 7 of the handle is joined to or arranged on a swingable lever 38 provided with a toothed segment 39 or the like which gears into a toothed sector 40 or the like which is fastened to the shaft 20 or is made in one piece with the sector 19.

According to the Fig. 8 the locking device 8 is in inactive position, whereby the locking device 30 catches into the cam-discs 13. When the locking device 8 by the upward movement of part 7 of the handle is brought into gear with the notch 9, the lever 38 is swung on the pin 37 whereby the segment 39 turns the sector 40 and thereby the sector 19 which gears into the toothed ring on 24, so that the notch 26 is brought opposite the notch 27 in the stationary ring. The roll 29 thereby catches into the two notches 26, 27, whereby the locking device is brought out of gear with the cam-discs and liberates them.

The device may of course be changed in many ways within the compass of the invention.

Having now described my invention, what I claim as new and desire to secure by Letters Patent is:

1. An improvement in calculating machines of the type wherein the crank for rotating the calculating wheels is associated with a locking device for locking the crank in zero position, characterized by the combination of a guiding device adapted to

maintain the locking device for the crank in inactive position during the rotating of the crank, and a locking device cooperating with a cam disk positively forced into engagement with the cam disks and locking the latter in relation to the calculating wheels when the locking device for the crank is brought to inactive position, the said locking device for the cam disks being brought completely out of gear with the cam disks and liberating them when the locking device for the crank is being brought into active position.

2. A device as claimed in claim 1 characterized by the provision of means for moving the locking device for the crank out of active position upon application of pressure thereto.

3. A device as claimed in claim 1 characterized in that the crank is mounted for swinging movement in a plane substantially at right angles to the plane of rotation thereof and includes an angularly disposed portion associated with the locking device.

4. A device as claimed in claim 1 characterized in that the crank is mounted for sliding movement.

5. A device as claimed in claim 1 characterized in that the guiding device includes a guiding member provided with a notch corresponding to the zero position of the crank, and a member adapted to move over the guiding member and adapted to drop into said notch.

In witness whereof I have hereunto signed my name.

VALENTIN JAKOB ODHNER.
